LIFTER FOR ROASTING SLING

Morris W. Moen, 628 9th Ave.,
Two Harbors, Minn. 55616

Filed June 30, 1969, Ser. No. 17,962

Term of patent 14 years

Int. Cl. D7—99

U.S. Cl. D44—29

FIG. 5

FIG. 1

FIG. 4

FIG. 3

FIG. 2

FIG. 1 is a front elevational view of a lifter for a roasting sling, showing my new design;

FIG. 2 is a top plan view;

FIG. 3 is a bottom plan view;

FIG. 4 is a side elevational view; and

FIG. 5 is a reduced scale perspective view, with a hand, roasting sling and roast shown in broken lines for purposes of illustrating environmental association only.

I claim:

The ornamental design for a lifter for roasting sling, as shown and described.
